CLAIM

The ornamental design for an auxiliary antenna mount, as shown and described.

DESCRIPTION

FIG. 1 is a perspective view of an auxiliary antenna mount taken from the lower portion of the antenna mount and showing my design;

FIG. 2 is a perspective view of the invention taken from the upper portion of the antenna mount;

FIG. 3 is a rear elevational view thereof;

FIG. 4 is a left side elevational view thereof, the right side forming a mirror image thereof;

FIG. 5 is a front elevation view thereof;

FIG. 6 is a top plan view thereof;

FIG. 7 is a bottom plan view thereof.
